UNITED STATES PATENT OFFICE.

WILLIAM A. READY, OF BROOKLINE, MASSACHUSETTS.

DESIGN FOR AN ESCUTCHEON PLATE FOR A DIAL MECHANISM.

Application filed July 24, 1928. Serial No. 27,568. Term of patent 7 years.

To all whom it may concern:

Be it known that I, WILLIAM A. READY, a citizen of the United States, and a resident of Brookline, in the county of Norfolk and State of Massachusetts, have invented a new, original, and ornamental Design for an Escutcheon Plate for Dial Mechanism, of which the following description in connection with the accompanying drawings is a specification, like characters on the drawings representing like parts.

Referring to the drawing which forms a part of my application:

Figure 1 is a front elevation of my new design for an escutcheon plate for use in connection with a dial mechanism for wireless apparatus; and

Fig. 2 is a side elevation of the device illustrated by Figure 1.

I claim:

The ornamental design for an escutcheon plate for a dial mechanism, as shown and described.

In testimony whereof, I have signed my name to this specification.

WILLIAM A. READY.
